(57) **CLAIM**

The ornamental design for the hanging sign, as shown and described.

DESCRIPTION

FIG. 1 is a perspective view of a first embodiment of a hanging sign showing my new design;
FIG. 2 is a front plan view thereof;
FIG. 3 is a back plan view thereof;
FIG. 4 right-side elevation view thereof;
FIG. 5 is left-side elevation view thereof;
FIG. 6 is a top elevation view thereof;
FIG. 7 is a bottom elevation view thereof;
FIG. 8 is a perspective view of a second embodiment of a hanging sign showing my new design;
FIG. 9 is a front plan view thereof;
FIG. 10 is a back plan view thereof;
FIG. 11 right-side elevation view thereof;
FIG. 12 is left-side elevation view thereof;
FIG. 13 is a top elevation view thereof;
FIG. 14 is a bottom elevation view thereof;
FIG. 15 is a perspective view of a third embodiment of a hanging sign showing my new design;
FIG. 16 is a front plan view thereof;
FIG. 17 is a back plan view thereof;
FIG. 18 right-side elevation view thereof;
FIG. 19 is left-side elevation view thereof;
FIG. 20 is a top elevation view thereof; and,
FIG. 21 is a bottom elevation view thereof.

The ornamental design which is claimed is shown in solid lines in the drawings. The broken lines in the drawings are for illustrative purposes only and form no part of the claimed design.
